COMBINATION WATER FRONT AND GRATE

J Skelt Parsons, Twila, Ky.

Application September 30, 1933, Serial No. 691,688

2 Claims. (Cl. 122—20)

This invention relates to combination water fronts and grates as employed in fire boxes of stoves of the type which use coal, coke, wood, or the like for fuel.

The objects of the invention are to provide a combination water front and grate adapted to be positioned in the fire box of a stove for supplying hot water for various purposes; to provide a unit which serves as a means of protecting and therefore insuring longer life to the fire box linings and grates and to further provide a device so arranged and constructed as to increase the heating capacity of such units. A further object is to provide means for removing ashes from the grates.

Referring to the accompanying drawing, which is made a part hereof and on which similar reference characters indicate similar parts,

Figure 1 is a partial plan view of a stove with a portion thereof in section and dotted outline showing the unit in position, and

Figure 2 is a perspective view of the device.

In the drawing reference character 10 indicates a stove of conventional type provided with a fire box 11 and the lining 12 surrounding the fire box.

The water front consists of the end members 13 connected by a relatively long side member 14. The end member 13 and the side member 14 are formed of the spaced plates 15 and 16 which are connected along their edges to form a channel for water. One of the end members 13 is provided with an inlet connection 17 and an outlet connection 18 fixed in any suitable manner to the outside plate 16. The outlet connection 18 is positioned above the inlet connection 17 and separated therefrom by means of a partition 19 fixed between the plates 15 and 16.

The grate is formed of a plurality of hollow members 20 extending from end to end and in communication with the channel formed by the plates 15 and 16. The members 20 are positioned near the bottom of the end members of the water front and are welded or secured in any suitable fashion to the plate 15.

In order to provide for removal of the ashes formed, the bars or rods 21 are provided having bent ends 22 connected to the under side of the end members 13 in any suitable manner to form a support for a shaker. The shaker is formed of a cross piece 23 provided with a series of projecting pins 24. A handle 25 is connected to the cross piece 23 and is provided with a ringed end 26. The cross-piece is mounted on the bars 21 in such a manner as to slide on the bars with the pins 24 extending upwardly between the hollow members

20 which form the grate and when pulled back and forth will shake the fire and cause the ashes to fall between the members 20 into the ash pit.

A depending loop 27 is provided on one of the end members 13 intermediate the bars 21 and serves as a support for the handle 25. The unit as described is positioned in the fire box as clearly shown in Figure 1, with the handle 25 projecting from the front. Suitable connections to a water supply are then made. Cold water enters the inlet 17 where it travels through the grate members 20 and enters the channel between the plates 15 and 16. When the outlet 18 is opened the water is withdrawn but due to the construction of unit it has traveled as indicated by the arrows 70 completely through the unit. The partition prevents the cold water entering the inlet 17 from traveling direct to the outlet 18. When it becomes necessary to remove the ashes the shaker is merely pulled back and forth, the projecting pins cause the ashes to become loosened and fall into the ash pit.

It may therefore be seen that a thin layer of water is provided on three sides of the fire box, this affords a greater heating surface exposed 80 to the fire and at the same time the water may be heated very quickly. The layer of water will also serve to prevent burning the linings and will prolong the life of these parts of the stove. No provision is made for heating water on the oven 85 side of the fire box as direct heat at this point is desired. The hollow members forming the grate likewise are protected by having water contained therein which prevents them from becoming burned out and they will therefore last much 90 longer than the usual form of grate bars.

The unit described above is so constructed and designed as to accomplish the objects set forth, it is inexpensive to construct and readily installed in stoves of the type mentioned and due to absence of a number of moving parts its serviceability and efficiency is evident.

Having thus fully described my said invention, what I claim as new and desire to secure by Letters Patent, is:

1. A water front and grate comprising hollow end members and a hollow side member connection in communication with each other, means positioned in one of said end members dividing it into inlet and outlet sections, connections to said 105 sections, and a series of hollow members forming a grate positioned between and in communication with the inlet section and the other end member thereby forming a channel to direct water from the inlet section through the grate to 110

100

110

the other end member, the side member and hence to the outlet section.

2. A water front and grate comprising end members and a side member forming a U-shaped channel, a partition separating one of said end members into upper and lower sections, an outlet connection to the upper section, an inlet connection to the lower section and a series of paral-

lel members forming a grate connected to and in communication with the lower section and the other end member to form a channel for circulating water from the inlet section through the grate members to the other end member, the side member hence to the outlet section. 80
